UNITED STATES PATENT OFFICE

EDWARD M. JONES, OF MACON, GEORGIA.

CREMATORY.

1,107,615.

Specification of Letters Patent. Patented Aug. 18, 1914.

Application filed December 30, 1913. Serial No. 809,552.

To all whom it may concern:

Be it known that I, EDWARD M. JONES, a citizen of the United States, residing at Macon, in the county of Bibb and State of Georgia, have invented a new and useful Crematory, of which the following is a specification.

This invention relates to crematories particularly designed for use in incinerating night soil, garbage, etc., one of the objects of the invention being to reduce the cost of construction; to provide means whereby the crematory can be charged with garbage or the like without necessitating the opening of the main door and the consequent loss of heat; and to provide means whereby the efficiency of the crematory is increased by utilizing the waste heat for the purpose of preheating air prior to its admission to the combustion chamber.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

85 In said drawings:—Figure 1 is a central vertical longitudinal section through the crematory, said section being taken on the line A—B Fig. 2. Fig. 2 is a central vertical transverse section through the crematory, said section being taken on the line C—D Fig. 1. Fig. 3 is a horizontal section on line E—F, Fig. 1. Fig. 4 is a section on line G—H, Fig. 3.

Referring to the figures by characters of reference 1 designates an incinerating chamber having a runway 2 in the bottom thereof provided with rails 3 on which a car 4 is adapted to travel. The top of the car is adapted to lie in the same plane with a platform 5 formed within one side portion of the incinerating chamber and extending from the front wall 6 of the rear walls 7 thereof. A grate 8 is located at or adjacent the center of the platform and a fuel door 9 is located at the outer end of the grate.

Stoke doors 10 can be arranged in the side and front walls as shown.

Erected at that side of the furnace remote from the platform 5 is a single stack 11 into the bottom of which open horizontal flues 12 having inlets 13 in the furnace wall close to the front and back ends thereof. Dampers 14 are arranged in these flues so that the flow of gases therethrough can be controlled. A partition 15 is arranged under the center of the stack and between the flues 12, as shown in Figs. 1 and 3.

The incinerating chamber is provided with the usual arched top or dome 16 which extends over the platform 5 and grate 8 and arranged above this top or dome 16 is a jacket 17 forming an air passage 18 which extends over the entire top 16, one end of the passage being open, as shown at 19, while the other end of the passage communicates with downwardly extending flues 20 opening into a horizontally extending flue 21. Air outlet passages 22 extend from the end portions of the flue 21 and into the end walls 6 and 7. Air spaces or pockets 23 are formed in certain of the walls, as shown.

The front and back walls 6 and 7 and the side walls 24 of the furnace are extended upwardly above the top 16 and have a desired number of fresh air inlets 25 which can be closed by suitable doors 26. A superstructure 27 suitably reinforced is supported by the walls 24 and above the top or dome 16 so that an air chamber 28 is thus formed 85 between the side walls of the crematory and between the said superstructure 27 and the jacket 17 and top or dome 16.

Arranged within the top of the crematory and above grate 8 is a charging chute 29, 95 as shown in Fig. 2. Arranged within the rear end wall of the crematory is another chute 30 the lower end of which projects into the incinerating chamber 1 and is adapted to overhang the car 4. This chute 30 is particularly designed for directing night soil onto the car.

A door 31 is provided for closing the front of the incinerating chamber after the car 4 has been placed therein, it being understood 105 that the runway 2 and the rails 32 therein extend through the door opening and to points outside of the crematory so that the car can be drawn from the crematory and brought to position where it can be con- 110

veniently loaded or unloaded. As shown in Fig. 3, the runway may be provided with a lateral extension 32 close to but outside of the crematory and within which the door 31 may move to open position. The door used in connection with the crematory does not, specifically, constitute any part of the present invention but has been fully described in a co-pending application filed by me.

In order that pre-heated air may be directed into the incinerating chamber, the passages 22, formed in the ends of the flue 21 are provided with outlets 34 opening into the incinerating chamber at the ends of the platform 5 and, in order that the flow of air to these outlets 34 may be properly controlled, dampers 35 are provided.

In using the crematory, the car 4 is loaded with the material to be incinerated and is then pushed into the incinerating chamber after which the door 31 is closed. Fuel is placed upon the grate 8 and ignited and the heat generated will be intensified by the pre-heated air supplied to the incinerating chamber from the passages 22, this pre-heated air being received from the passage 18 where it comes into direct contact with the highly heated top or dome 16 of the chamber 1. Air is supplied to the passage 18 through the inlets 25 and the chamber 28. By opening the rear damper 14 and closing the front damper 14, the hot gases issuing from above grate 8 will flow rearwardly over the platform 5 and thence across the rear portion of the car and into the rear flue 12. By closing the rear flue 12 and opening the front damper 14, the hot combustion products will flow across the incinerating chamber to the inlet of the front flue 12. By opening both of the dampers 14 the hot gases will be divided into two currents, one current passing across the rear portion of the incinerating chamber while the other current will pass across the front portion of the chamber 1. Pre-heated air from outlets 34 can be controlled in a like manner. As both of the flues 12 discharge into the single stack 11, it will be seen that an equal draft will be set up through both flues 12. Furthermore, as only one chimney is necessary by reason of the peculiar construction set forth, the cost of building the crematory is materially reduced. By utilizing pre-heated air in the manner described, the reduction of the material upon the car will be speedily effected. By depositing garbage or the like within the chute 29, it will be fed onto the platform 5 and grate 8 in the manner hereinbefore described and the hot gases generated, together with the pre-heated air, will quickly incinerate the material. By utilizing the chute 30, night soil can be deposited on the car and by opening the rear flue 12 and closing the front flue, the hot gases issuing from above grate 8 and through the outlets 34

will flow directly over the deposited material and quickly incinerate it.

It will be seen that by providing the crematory with the charging chutes described, the loss of heat resulting from the constant opening and closing of the main door is avoided. Furthermore by utilizing means for pre-heating air and for supplying the pre-heated air to the rear as well as the front portion of the crematory, the distribution of the heated air and combustion products within the crematory is more efficiently effected and, consequently, the crematory operates to more quickly reduce the garbage, etc., supplied thereto, than would otherwise be possible.

What is claimed is:—

1. A crematory including an incinerating chamber, a platform along one side of the chamber and having an air inlet opening at each end, a grate extending into the platform at a point between its ends for supporting ignited material, an outlet flue at the opposite side of the incinerating chamber, and means for directing air over the incinerating chamber to preheat it and thence through the openings at the ends of the platform and into the incinerating chamber, said air inlets at the ends of the platform being arranged to direct the inflowing air in a direction transverse to the direction of the flow of the gases through the incinerating chamber.

2. A crematory including an incinerating chamber having a platform extending along one side thereof, outlet flues at the other side of the incinerating chamber, there being air inlets at the ends of the platform, a grate for supporting combustible material at one side of the center of the platform, means for directing air over the incinerating chamber to preheat it and thence through the inlets, thereby to support combustion of material upon the platform and grate, said air inlets at the ends of the platform being so arranged as to direct the inflowing air in a direction transverse to the direction of the flow of the gases through the incinerating chamber.

3. A crematory including an incinerating chamber having a platform along one side, a runway or depression between the platform and the other side, and an outlet flue in that side of the chamber adjacent the runway, a grate extending into the middle portion of the platform from one side of the incinerating chamber, there being air inlets at the ends of the platform, means for directing fresh air over the top of the incinerating chamber to preheat the air and thence to the inlets at the ends of the platform to support combustion within the incinerating chamber, and means for directing the material to be incinerated into the incinerating chamber at a point in the path of the preheated air issuing from the inlet and the gases arising from

the grate, said gases and preheated air being adapted to flow to one or both of the outlet flues, said inlets at the ends of the platform being so arranged as to direct the inflowing air in a direction transverse to the direction of the flow of the gases through the incinerating chamber.

4. A crematory including an incinerating chamber having a runway within one side portion thereof, outlet flues in said side portion, a platform along the other side of the chamber, there being air inlets at the ends of the platform, a grate extending into the platform adjacent the center of one side, an air chamber above the incinerating chamber and having a fresh air inlet, means for directing fresh air along a tortuous path within said chamber and to the inlets at the ends of the platform, thereby to preheat the air, and

means for directing material to be incinerated, into the chamber at a point in the path of the air currents issuing from the inlets and the gases arising from the grate, said air currents and gases being adapted to flow to one or both of the flues in the side of the incinerating chamber, said air inlets at the ends of the platform being so arranged as to direct the inflowing air in a direction transverse to the direction of flow of the gases through the incinerating chamber.

In testimony that I claim the foregoing as my own, I have hereto affixed my signature in the presence of two witnesses.

EDWARD M. JONES.
